UNITED STATES PATENT OFFICE.

EMIL SPECK, OF PATERSON, NEW JERSEY, ASSIGNOR TO THE TAYLOR-FRIEDSAM COMPANY, OF NEW YORK, N. Y., A CORPORATION OF NEW JERSEY.

DESIGN FOR A RIBBON, TEXTILE FABRIC, OR ARTICLE OF SIMILAR NATURE.

Application filed March 2, 1923. Serial No. 5,344. Term of patent 3½ years.

To all whom it may concern:

Be it known that I, EMIL SPECK, a citizen of the United States of America, and resident of the city of Paterson, county of Passaic, State of New Jersey, have invented a new, original, and ornamental Design for a Ribbon, Textile Fabric, or Article of Similar Nature, of which the following is a specification, reference being had to the accompanying drawing, forming part thereof.

The figure is a plan view of a ribbon, textile fabric or article of similar nature, illustrating my new and ornamental design.

I claim:

The ornamental design for a ribbon, textile fabric, or article of similar nature as shown.

EMIL SPECK.
